Oreg.

Application October 20, 1947, Serial No. 780,991

3 Claims. (Cl. 268—59)

1

This invention relates to improvements in power driven door operating mechanisms.

The general object of the invention is to provide an improved power operated mechanism for opening and closing doors wherein the door movement in either direction is initiated by a convenient push button switch and terminated by arrival of the door or doors in their proper open or closed positions, as the case may be.

A further object is to provide an improved door operating mechanism, particularly adapted for use with overhead garage doors and the like, and designed to reverse the movement of the door automatically if it should encounter an obstruction in its closing movement.

Another object is to provide an improved construction for the purpose described which is relatively simple and inexpensive to manufacture, and sufficiently rugged and reliable to give long service in automatic door operation without adjustments or repairs.

Other objects and advantages reside in the details of construction and arrangement of parts shown in the accompanying drawings illustrating a preferred embodiment of the invention.

In the drawings:

Figure 1 is a top plan view of the preferred embodiment of door operating mechanism;

Figure 2 is a side elevation view;

Figure 3 is a side elevational view of the present mechanism applied to an overhead garage door;

Figure 4 is a cross sectional view taken on the line 4—4 of Figure 1;

Figure 5 is a schematic diagram of the operating mechanism and its associated control circuits, showing the mechanism at an intermediate point in its door opening movement; and

Figure 6 is a view similar to Figure 5, showing the parts at rest in open door position.

The door operating mechanism illustrated in Figures 1 and 2 may be applied to single and double doors on vertical hinges, and to overhead doors of various types such as are commonly used in garages and the like. It is, therefore, to be understood that the invention is not limited to the particular type of overhead door movement which is shown and described merely for the purpose of illustrating the action of the operating mechanism.

In Figure 3 the door 10 is mounted to close a doorway 11 in a garage or other building 12. The present door operating mechanism, indicated generally by the numeral 13, is mounted horizontally above the level of the top of the door-

2

way to extend inwardly at right angles to the center top of the door frame. The door operating mechanism 13 is constructed as a self-contained unit which may be secured at one end to the building or door frame with the other end supported by a bracket 14, or the like, from the ceiling or other convenient support.

The door shown in Figure 3 is supported at its four corners from movement from a vertical closed position to a horizontal overhead open position. Two of these points of support comprise pivotal connections 15 with rigid lever arms 16 at the lower corners of the door. Each arm 16 is fulcrumed in a bearing 17 on a side frame 15 of the doorway and has an inwardly extending short arm 18 connected with a counterbalancing spring 19 anchored at 20 on the door frame some distance beneath the pivotal support 17. The two upper corners of the door are carried by 20 rollers adapted to ride in tracks 21 on opposite sides of the door frame at the top of the doorway. The arrangement is such that in closing, the top of the door moves to the forward end of the tracks 21 and the bottom of the door swings 25 downwardly until the arms 16 are in substantially vertical positions with the short arms 18 in slightly overcenter positions. In opening, the top of the door moves rearwardly on the tracks 21 and the bottom of the door swings outwardly 30 and upwardly on the ends of the arms 16 until these arms extend upwardly in a substantially vertical position with the bottom of the door supported at the top of the doorway opening.

The various parts of the operating mechanism 35 13 are mounted on a pair of longitudinal members 25, such as channels or angle irons, having a requisite shape and stiffness to form a guide track for a sliding carriage 26. The carriage 26 is moved longitudinally on the track members 25 40 by a chain 27 trained over a pair of end sprockets 28 and 29. The sprocket 28 is mounted on an idler shaft 30 at the outer or door end of the tracks 25, and the sprocket 29 is mounted on a driving shaft 31 at the inner end of the tracks. 45 The shaft 31 is driven by a pulley 32 connected by a belt 32a with a reversible single phase induction motor 33 which may be mounted under the tracks 25 as shown. The opposite ends of the chain 27 are connected to the carriage 26 50 so that when the motor 33 rotates in one direction the carriage is pulled to the outer end of the track and when the motor rotates in the opposite direction the carriage is pulled to the inner end of the track. A link 34 pivotally connects the carriage 26 with the top of the door 55

to cause this part of the door to travel with the carriage, the door being supported and guided by the tracks 21 and the carriage being supported and guided by the tracks 25.

A somewhat resilient connection is provided by the belt 32a between the motor and the driving sprocket 29 to avoid jamming of the parts and possible damage to the mechanism if the movement of the door is suddenly stopped, as by encountering a solid object in its path of descent. A gear drive has a tendency to jam under such circumstance, locking the mechanism and preventing reversal of the motor.

The carriage 26 is provided with an upstanding lug or post 35 to engage an arm 36 on a bell crank lever 38 in approaching open door position, and to engage an arm 37 on this lever in leaving open door position, to shift the lever to different positions in accordance with the direction of movement of the carriage and the door 10. A push rod 39 connects the lever 38 with a reversing switch 40.

The chain 27 carries a lug 41 on its upper reach and a lug 42 on its lower reach, each of these lugs being engageable with a sliding bar 43 to actuate a lever 44 mounted on a switch box 45. These parts are arranged to operate a limit switch in the switch box 45 to deenergize the motor 33, the upper lug 41 engaging the bar 43 as the door arrives in substantially fully closed position and the lower lug 42 engaging the bar as the door arrives in substantially fully open position. As best shown in Figures 5 and 6, the bar 43 is mounted for longitudinal sliding movement in a guide 46 wherein it is biased by a spring 47 to move to the right to occupy normally the position shown in Figure 5. One end of the bar 43 is provided with an angular L-shaped extension 48 disposed across both upper and lower reaches of the chain 27 in a position to be engaged and moved by either one of the chain lugs 41 and 42 as one or the other of these lugs approaches the sprocket 29. The other end of the bar 43 carries a pivotally mounted detent 49 biased by a spring 50 to a position at right angles to the bar to engage and move the end of the lever 44 when the bar is moved to the left by one of the lugs 41 or 42. When the bar 43 is again returned to its Figure 5 position by the spring 47, the detent 49 is adapted to pivot to ride over the end of the lever 44.

The electric circuits for the operating mechanism are energized from a source of supply 51. The power circuits for the motor 33 are energized through a pair of lines 52 under the control of a limit switch 53 in the switch box 45. Closing of this switch completes a circuit to a running circuit 54 and to the reversing switch 40 in a starting circuit 55. When the reversing switch 40 is in its lower position as shown in Figure 5, the starting circuit 55 is conditioned for motor rotation in a direction to open the door, producing chain movement in the direction indicated by the arrow 56. When the starting switch is in its upper position as shown in Figure 6, the starting circuit is conditioned for motor rotation in the opposite direction to produce a closing movement at the door wherein the chain moves in a direction counter to the arrow 56. The present circuits are designed for an induction motor having a switch 57 incorporated therein to open the starting circuit as soon as the motor attains its normal operating speed. The numeral 58 designates a centrifugal device on the motor shaft 60 operating through a bell crank lever 61 to

open the switch 57 when operating speed is attained. At all times when the motor is not operating at substantially its normal speed, a spring 62 maintains the switch 57 in closed position in a manner well understood in the art to close the circuit 55 for starting in a direction determined by the position of the reversing switch 40.

The limit switch 53 is connected with the lever arm 44 in such a way that it is normally biased to closed position by a spring 65 which pulls the arm against a stop 66 as shown in Figure 5. When one of the lugs 41 or 42 engages the sliding bar 43, the pawl 49 moves to the left to rotate the lever arm 44 in a counterclockwise direction about its fixed pivot 67 to open the switch 53. After the switch has thus been opened it is maintained in open position by a stop 68 which is pivotally mounted at 69 and biased by a spring 70 to the position shown in Figure 6. Disposed adjacent the stop 68 is a solenoid 71 having a plunger 72 constituting a magnetic armature movable within the solenoid coil. The solenoid is energized by a circuit 73 under the control of a push button switch 74. When the switch 74 is momentarily closed, the plunger 72 makes a single stroke, striking the stop 68 and releasing the lever arm 44 to allow the spring 65 to close the switch 53.

When the door is fully opened the various parts are in the rest positions shown in Figure 6, with the lug 42 holding the bar 43 extended to the left after having opened the limit switch 53 in the previous opening movement. Stop 68 holds the limit switch open to permit overtravel of bar 43, and spring 62 holds the starting switch 57 closed, reversing switch 40 being in its upper position. When it is desired to close the door the switch 74 is momentarily closed, causing the plunger 72 to make a stroke against the stop 68 to release the lever arm 44, allowing the limit switch 53 to close. This action energizes the running circuit 54 and energizes the starting circuit 55 to start the motor in the proper direction to produce chain movement counter to the direction indicated by arrow 56. As soon as the motor attains operating speed the centrifugal device 58 opens the starting switch 57 and continues to hold it open. Upon leaving open door position bar 43 follows lug 42 to the right causing pawl 49 to override the end of arm 44, placing these parts in their Figure 5 position. The post 35 then engages the upstanding arm 37 on the bell crank lever 38 and moves the reversing switch 40 to its lower position to condition the starting circuit for reverse rotation of the motor whenever it is again called upon to start. If there is no obstruction in the way of the door it proceeds to fully closed position, the motor being then stopped by engagement of the lug 41 with the sliding bar 43 to open the limit switch 53 at the proper time so that the door will be fully closed when the parts have come to rest. If, however, the door encounters an obstruction in its closing movement, the speed of the motor 33 will be materially retarded, causing the centrifugal device 58 to yield to the action of spring 62 to reclose the starting switch 57. The polarity of the starting circuit having been just reversed by the reversing switch 40, the motor is thereby immediately stopped and restarted in the opposite direction to reopen the door. When the motor attains its normal operating speed the starting switch 57 is again opened and the motor operates on its running circuit

54, which is effective for either direction of rotation, until the lug 42 engages the sliding bar 43 to open the limit switch 53 with the door fully open.

The door is opened from a fully closed position by momentarily closing the switch 74. This causes the plunger 72 to release the stop 68 from the lever arm 44 in the same manner as in closing the door, since when the door is fully closed the switches 53 and 51 are in the respective positions shown in Figure 6, but the sliding bar 43 is held to the left by the lug 41 instead of the lug 42. By virtue of the fact that the carriage and post 35 move to the right in closing the door, the reversing switch 40 will be in its lower position when the door is fully closed. With the closing of limit switch 53 when the parts are in these positions the running winding 54 is energized and the starting winding 55 is energized to produce motor rotation for chain movement in the direction of the arrow 56 to open the door. As the carriage 26 approaches open door position, the post 35 engages the arm 36 on the bell crank lever 38 and returns the reversing switch 40 to its upper position just before the lug 42 engages the sliding bar 43 to open the limit switch 53 to stop the motor.

Thus it is seen that the single limit switch 53 is utilized to stop both the opening and closing movements of the door and also to initiate either of these movements by the action of the plunger 72 in response to momentary closing of the push button switch 74. If the door is open, a momentary closing of this switch will cause the door to close, and if the door is closed the same operation of the switch 74 will cause it to open. The reversing switch 40 always rests in the proper position to reverse the motor when it is restarted, and by virtue of the fact that the bell crank lever arm 38 is positioned close to the open door position of the post 35, the starting circuit is conditioned for a door opening movement just after the initiation of each door closing movement. For this reason any obstruction encountered by the door after it starts to close will be effective to reopen the door because as soon as the motor 33 slows down enough for spring 62 to overpower the centrifugal device the motor will be reversed by the pre-conditioned starting circuit.

This mechanism thereby accomplishes all the necessary functions of a fully automatic power operated door, including the safety feature of self-reversal when there is an obstruction beneath the door, and requires considerably fewer parts than conventional power operated door opening and closing mechanisms capable of performing these functions. The mechanism is rugged and self-contained and adapted to be mounted as a unit in a building for operating any conventional type of doors under simple push button control. Various changes may of course be made in the arrangement of parts and details of construction within the scope of the appended claims.

Having now described my invention and in what manner the same may be used, what I claim as new and desire to protect by Letters Patent is:

1. A door operating mechanism comprising an endless chain having two reaches adapted to move in opposite directions to open and close a

door, a reversible motor for driving said chain, a limit switch for controlling the energization of said motor, means for closing said switch to start said motor, a movable member for opening said switch to stop said motor, a lug on one reach of said chain to engage said member to stop said motor when said chain arrives at open door position, a lug on the other reach of said chain to engage said member to stop said motor when said chain arrives at closed door position, a starting circuit for said motor, a reversing switch in said circuit, means operable by said chain in approaching and leaving open door position to alternately change said reversing switch to condition said starting circuit for opposite motor rotation, and means comprising a speed responsive switch in said starting circuit to reverse the rotation of the motor if the closing movement of the mechanism is retarded after said reversing switch has been actuated.

2. In a door operating mechanism movable between open and closed door positions, a reversible motor for operating said mechanism, starting and running circuits for said motor, a limit switch controlling both of said circuits, means for closing said limit switch to start the motor, means operable by said mechanism at both of said door positions to open said switch to stop the motor, a reversing switch in said starting circuit, means operable by said mechanism in approaching and leaving its open door position to actuate said reversing switch, and means comprising a speed responsive switch in said starting circuit to reverse the rotation of the motor in response to retardation of the closing movement of the mechanism after said reversing switch has been actuated.

3. A door operating mechanism comprising a chain connected with the door, a reversible motor for driving said chain between open and closed door limit positions, starting and running circuits for said motor, a limit switch controlling both of said circuits, means for closing said switch to start the motor, a movable member for opening said switch to stop the motor, means on said chain to engage said member and open said switch in open door position of the chain, means on the chain to engage said member and open said switch in closed door position of the chain, a reversing switch in said starting circuit, means on said chain to actuate said reversing switch as said chain is approaching and leaving its open door position, and means comprising a speed responsive switch in said starting circuit to reverse the rotation of the motor if the closing movement of the mechanism is retarded after said reversing switch has been actuated.
